UNITED STATES PATENT OFFICE.

ANTOINE ANDRE, OF CHICAGO, ILLINOIS.

IMPROVED DEVICE FOR STOPPING BOTTLES.

Specification forming part of Letters Patent No. **38,367.** dated May 5, 1863.

To all whom it may concern:

Be it known that I, ANTOINE ANDRE, of Chicago, in the county of Cook and State of Illinois, have invented a new and Improved Device for Stopping Bottles, &c.; and I do hereby declare that the following is a full, clear, and exact description of the same, reference being had to the accompanying drawing, making a part of this specification.

The drawing represents a vertical central section of my invention.

This invention consists in the employment of a screw-valve fitting into a seat that is secured to the neck of a bottle in combination with a funnel-shaped mouth-piece in such a manner that by the aid of said valve the communication between the interior of the bottle and the mouth-piece can be effectually stopped, and that on opening the valve the contents of the bottle can conveniently be poured out, or by the aid of the funnel-shaped mouth-piece fresh liquid can be introduced into the bottle with ease and convenience.

To enable others skilled in the art to make and use my invention, I will proceed to describe its construction and operation with reference to the drawing.

The stem of the valve A, which is intended to stop a bottle, is provided with a screw-thread, a, screwing into a socket, b. This socket is formed by a hole drilled or cast into a projection, c, extending from the side of the casting B, which contains the valve-seat d. This seat, which may be protected by a washer, e, of india-rubber or leather, or other suitable material, connects by annular passage, f, with the interior of the bottle; and a channel, g, leads from the socket b to the funnel-shaped mouth-piece C, forming the top of the casting B, as clearly shown in the drawing. The casting B is connected by a screw-thread, h, with a ring, D, which is firmly secured to the mouth

of the bottle. When the valve A is screwed up tight against the seat d, the communication between the passage f and channel g is interrupted, and the bottle is firmly stopped; but if the valve A is unscrewed, a communication is effected between the passage f and channel g, and the contents of the bottle can be poured out. The shape of the mouth-piece C is such that the operation of pouring out the contents of the bottle can be effected without danger of soiling the outside of the bottle, and at the same time, by having the interior of the mouth-piece funnel-shaped, the operation of filling the bottle is considerably facilitated. A device of this description, when once attached to the bottle, can be used for a long time, and if the bottle breaks it can be attached to another bottle without much difficulty. It will save the necessity of buying new corks whenever the bottles have to be stopped, and the bottles can be opened without the use of a corkscrew simply by unscrewing the valve A.

The valve A and the casting B ought to be made of such material as will not be affected by the contents of the bottle, and as a general thing said parts will be constructed of tin or some other metal covered with tin. They might, however, be also made of hard india-rubber or of glass, or of any other convenient material.

Having thus fully described my invention, what I claim as new, and desire to secure by Letters Patent, is—

A device for stopping bottles, having in combination a screw-valve, A, passage f, channel g, and funnel-shaped mouth-piece C, all arranged and operating in the manner and for the purpose described.

A. ANDRE.
